EARTH TAMPER FOR CONCRETE HIGHWAY
SIDE FORMS

Frank Creason, Excelsior Springs, Mo.

Application April 9, 1932, Serial No. 604,304

34 Claims. (Cl. 94—48)

This application is a continuation in part of my original U. S. patent application Serial No. 535,019, filed May 4, 1931.

In the construction of concrete highways, it is customary to lay heavy metal side forms along the grade to retain the concrete when poured and to support the heavy concrete finishing machines. It is essential that the side forms be held against downward springing to any appreciable extent and that all spaces between them and the ground be filled, and it is therefore customary to tamp earth solidly under said side forms, by hand. It is the principal object of my invention to provide a simple, inexpensive and economical motor-actuated machine for performing the earth-tamping operation, said machine being of such nature as to not only accomplish the same amount of work now requiring a number of men, but to perform the tamping more thoroughly.

It is very often customary on account of inadequate appropriations, to construct half the width of a concrete highway at one time and to later add the other half when funds are available. In adding this last half, one of the side form is necessarily placed rather close to one edge of the previously completed half and the space necessarily left between the two halves is later filled in with concrete. This space is insufficient to allow operation of one of the twin tamping means of the machine therein, and it is therefore a further object of the invention to provide a unique construction in which said one tamping means may be raised to a position above the side form so that the machine may be operated to at least tamp the earth under and in contact with said side form at the inner side of the latter.

Another object of the invention is to provide a machine which will be well balanced by the tamping means at opposite sides of the side form, along and under which the earth is being tamped.

A still further object is to provide a machine which may readily be conditioned to operate upon side form of one width and height, or upon another width and height, there being two sizes of these forms commonly in use.

With the foregoing and minor objects in view, the invention resides in the novel subject matter hereinafter described and claimed, description being accomplished by reference to the accompanying drawings.

Fig. 1 is a perspective view showing one side of the machine.

Fig. 2 is an enlarged perspective view showing the other side of the machine.

Fig. 3 is a side elevation partly in section of the side of the machine shown in Fig. 2, showing the tamping means at said side swung upwardly to an inoperative position.

Fig. 4 is a bottom plan view.

Fig. 5 is a detail horizontal sectional view on line 5—5 of Fig. 2 showing part of the means for holding the shiftably mounted tamping means in lowered position.

Fig. 6 is a fragmentary perspective view showing the latch which is instrumental in holding the aforesaid shiftably mounted tamping means in operative position.

Fig. 7 is a vertical transverse sectional view substantially on line 7—7 of Figs. 1 and 4.

Figs. 8 and 9 are fragmentary perspective views of spacers which are used in conditioning the machine for operation upon larger side forms.

The machine herein disclosed embodies a carriage C constructed to travel upon a side form F, twin tamping means T and T' mounted on said carriage in laterally spaced relation to straddle the side form F, a small motor M mounted on the carriage C, and actuating connections between said motor and the actual earth tampers 10 and 10' of the twin tamping means T and T'. The tamping means T' is ordinarily in a lowered position as shown in Figs. 2, 4, 6 and 7 and the tamping means T is always in the lowered position shown in Figs. 1, 4 and 7, but in case there is insufficient room at the outside of the side form F to allow operation of said tamping means T', it may be vertically shifted (preferably swung) to a position above said side form, as illustrated in Fig. 3. While this can be effected any time an obstruction exists at the outer side of the side form, it is usually done only when laying the second half of a concrete highway, as previously explained herein. When the tamping means T' is lowered, this tamping means and the tamping means T, straddle the side form F and the tampers 10 and 10' solidly pack the earth under and in contact with said side forms, and the tamping means T will effectively perform its work at the inner side of the side form F when the tamping means T' is raised.

The machine is propelled by the motor M, along the side form, and a transport wheel 11 and transport handle 12, are employed for use when the machine is to be taken from the side form and transported from one point to another, said wheel 11 and 55

handle 12 being both mounted in novel ways as hereinafter described. The wheel 11 normally occupies an idle position in which it may roll upon the side form F as shown in Fig. 1, and the handle 12 then stands upright as shown in this view, so that the hand grips 13 may be held in the operator's hands to steady the machine against lateral tilting while in use. The wheel 11 and handle 12 however, may both be moved 10 to and held in lowered positions when the machine is to be moved upon the ground, and in Fig. 3, the handle has been shown in transport position.

Specific details of the machine herein disclosed 15 will now be described, with the understanding however that within the scope of the invention as claimed, minor variations may be made.

The carriage C embodies a base formed primarily of a length of channel metal 14 whose 20 side flanges 15 and 16 project downwardly for disposition at opposite sides of the form F, and between the rear ends of these flanges, a brace plate 17 is shown. The carriage C is provided with double-flanged rollers 18 secured upon 25 front and rear transverse shafts 19 and 20 which are connected by a chain 21 and suitable sprockets. Both shafts 19 and 20 pass through vertical notches 22 in the flanges 15 and 16 and are rotatable in suitable bearings 23 secured by 30 bolts 24 against the outer sides of said flanges. These flanges are formed with vertically spaced bolt holes 25 allowing relative vertical adjustments of the carriage base 14 and the shafts 19 and 20, according to the height of the side form 35 F or the extent which the tamping means must be spaced from the ground to obtain the best results. The rollers 18 may be of one length or another, according to the width of the side form, and the twin tamping means T and T' may be spaced apart one distance or another, according to 40 said width.

At the edge of the carriage base 14 for disposition at the inner side of the form F, is a horizontal plate 26 having a vertical longitudinal flange 27 secured by bolts or the like 28 to the flange 15, said flange 27 being formed with a notch 29 through which the shaft 20 passes. The rear end of plate 26 is forwardly spaced from the rear end of the carriage base 14 and is provided with a transverse downwardly projecting vertical flange 30. At the rear side of this flange 30 and rigidly bolted or otherwise secured in the angle between said flange 30 and the flange 15, is a vertical tamper mount 31 which is preferably of the channel shape shown, said mount projecting both upwardly and downwardly from the carriage base 14 and being provided at its lower end with a guide 32 for the tamper 10, said guide being so positioned that said tamper diverges upwardly from the inner side of the form F in position to tamp the earth under and in contact with said form.

Directly opposite the tamper mount 31, is a vertical plate 33 which is secured at its lower 65 end to the flange 16, by bolts or the like 34. The upper end of plate 33 is at about the same elevation as the upper end of the tamper mount 31, and said upper ends are secured to a transverse member 35, said member 35 having down- 70 turned ends to one of which the tamper mount 31 is bolted at 36, and to the other of which the plate 33 is secured by bolts or the like 36'. When the machine is to operate upon a wider side form, the cross member 35 may be entirely 75 removed and a longer cross member 35' (Fig. 9)

substituted. The lower end of plate 33 is then spaced outwardly from the flange 16, by the spacer 37 shown in Fig. 8, said spacer being secured to the plate 33 by the bolts 34 and being secured to the flange 16 by other bolts (not shown) which may be inserted through the bolt holes 38 of the spacer and through the bolt holes 39 of the flange 16. 5

At the outer side of the plate 33, is a second tamper mount 31' which is substantially a duplicate of the mount 31, the lower end of said mount 31' being provided with a guide 32' for the tamper 10'. By any desired means, such as the two washers 40 and 41 and the bolts 42 (Fig. 7), the tamper mount 31' is mounted upon 10 the plate 33 so that said mount may either occupy a vertical position as shown for instance in Figs. 2 and 7, or an upwardly swung position as shown in Fig. 3. A single latch 43 (Figs. 6 and 3) may well be employed to hold the mount 15 31' in raised position and to assist in holding it in lowered position, said latch being adapted to abut one edge or the other of the plate 33. When the mount 31' is in its vertical position, a hook 44 on its front side receives the front 20 edge portion of the plate 33, and a flange 45 projecting rearwardly from said mount, is receivable in a rigid hook 46 on the rear end of a short plate 47 which is interposed between the lower end of plate 33 and the flange 16, and is 25 secured by the bolts 34. The front end of plate 47 is rearwardly spaced from the front edge of the plate 33, so that the hook 44 may enter 30 between said plate 33 and the flange 16, as shown in Fig. 5. 35

Secured in the upper end portions of the channels of the two tamper mounts 31 and 31', are two horizontally aligned bearings 48 and 48' respectively, in which a transverse horizontal shaft 49 is rotatably mounted, said shaft being 40 driven by a V-belt 50, pulleys 51 and 52, and a clutch 53, from the motor M. This shaft 49, through the instrumentality of suitable chains 54 and 55, and coaxing sprockets, drives the shaft 19, effecting driving of both rollers 18 to propel 45 the machine along the side form. These driving connections between the shafts 49 and 19 are shown most clearly in Fig. 3.

The ends of the shaft 49 are provided with eccentrics 60 and 60' respectively, disposed at the 50 outer sides of the tamper mounts 31 and 31', and by means of resilient pitman rods 61 and 61', said eccentrics are connected with bell cranks 62 and 62' which are fulcrumed in the channels of the mounts 31 and 31' respectively. 55 The bell crank 62 is directly pivoted to the tamper 10 and the bell crank 62' is similarly pivoted to the tamper 10'. Rotation of the shaft 49 thus serves to effect reciprocation of both of these tampers, and the yieldable pitman rods 61 and 61' allow for any variance in the travel of 60 said tampers, occasioned by contact thereof with stones, unusually hard earth, etc.

Rotation of the shaft 49 may be started or 65 stopped by means of the clutch 53, and to control said clutch, a vertical clutch lever 63 and a hand-operated cam lever 64 are preferably employed, said cam lever being mounted on the cross member 35.

The pitman rods 61 and 61' are preferably 70 of the construction detailed in Fig. 3. At its ends, the rod embodies two blocks 65 and 66 respectively, the one connected with the eccentric and the other with the bell crank. U-shaped yokes 67 and 68 straddle the blocks 65 and 66 75

respectively and are pivoted thereto at 69 and 70, on axes at right angles to the block pivots. A rod 71 extends between the two yokes, passes slidably through openings 72 and 73 thereof and is provided with heads 74 and 75 lying within said yokes. A coiled compression spring 76 surrounds the rod 71 and at its ends abuts the yokes 67 and 68. Not only does the pitman rod constructed in this manner, allow for variations in the travel of the tamper, but the operation of the machine as a whole is materially cushioned thereby.

The transport wheel 11 above mentioned is rotatable upon a stub-axle 77 which is carried by the front end of an arm 78, the rear end of this arm being provided with a transverse shaft 79 slidable through guide openings in the flanges 15 and 16, the opening of the flange 16 being shown at 80 in Fig. 2. A collar 81 is secured on shaft 79, and a coiled compression spring 82 surrounds said shaft and bears at its ends against the flange 15 and said collar, holding the shaft in a position shifted endwise in one direction. When the arm 78 is in the raised position herein shown, it overlies an abutment 83 (Figs. 1 and 4), said abutment having an upper edge 84 so inclined as to effect sliding of the shaft 79 against the action of the spring 82, when the arm 78 is forced downwardly. Hence, as soon as the arm 78 is moved downwardly sufficiently far to clear the abutment 83, it will be snapped under said abutment by the spring 82, it being thus insured that the arm 78 and wheel 11 shall be held in lowered position when it is desired to transport the machine.

The transporting handle 12 is provided with an oblique front end 85 which is rotatably received in an inclined bearing 86 secured to the rear portion of the carriage base 14. Suitable means 87 is employed for contracting the bearing 86 to hold the handle end 85 against accidental turning, but upon release of said means 87, the handle may be swung from the vertical position of Fig. 1 to the lowered position of Fig. 3, or vice versa. Tightening of the means 87 then holds the handle in the position to which it has been moved.

I preferably mount an oil tank 88 upon the carriage and provide said tank with an air-compressing pump 89 and with an oil discharge tube 90 (Fig. 4), said tube being positioned to spray oil upon the inner side of the form F, as the machine advances. Thus, the necessary form oiling is accomplished simultaneously with tamping. The other tank 91, is merely the fuel tank of the motor M. 92 is the motor muffler and 93 suitable foot-starting mechanism. The tank 88 has been omitted from Fig. 3.

With the machine resting upon the side form, it is propelled along the latter and the twin tamping means T and T' operated, thereby effectively tamping the earth under and in contact with said side form. Whenever, for one reason or another, there is not ample space to allow operation of the tamping means T', the latter may be swung upwardly as shown in Fig. 3 and held until its use is permissible. During the tamping operation, the handle 12 stands upright as in Fig. 1, and hence may be instrumental in allowing the operator to hold the machine against lateral tilting. Lateral steadyng pressure may be exerted upon the hand grips 13 to hold a guide shoe 94 at the lower end of the mount 31, against the inner side of the form

F, said shoe being shown in Figs. 1 and 4. Ordinarily, however, no such attention will be required, for in constructing the machine, the weight of carriage-supported parts is so placed as to slightly overbalance the carriage toward the inner side of the form F. This causes the machine to have a continual tendency to tilt toward the inner side of the side form, but such tilting is prevented by the shoe 94 which slides along the inner side of the side form while the flanged rollers 18 are being slowly driven along the upper edge of said form. The machine will thus maintain itself upright, and being guided by the side form and self-propelled, it may continuously advance and pack the earth continuously during such advancing, without requiring any attention except as to motor operation, lubrication, etc. Even if the tampers 10 and 10' encounter stones or an excess of dirt, and cannot therefore move downwardly to normal extent, they will not exert upward unbalancing thrusts tending to tilt the machine from the side form, due to the resilient nature of the pitman rods 61 and 61'. Attention is invited to Fig. 1 showing the motor M mounted partly on plate 14 and partly on the laterally projecting plate 26, thereby slightly overbalancing the machine toward the inner side of the form F, as above explained.

Whenever the machine is to be transported, handle 12 may be swung to the position shown in Fig. 3, and the wheel 11 pushed downwardly until its carrying arm 78 snaps under the abutment 83. The machine may then be pushed easily from place to place, as a wheelbarrow.

While a preferred construction has been herein illustrated, numerous variations may be made within the scope of the invention as claimed, and it is to be understood that I am not therefore restricted to the specific disclosure herein made.

I claim:

1. A machine for tamping earth under a concrete side form which rests directly upon the ground, comprising a carriage constructed to travel upon said side form and to maintain one relation with said side form during the whole of its travel, a tamper constructed and positioned for delivering blows transverse to the side form in a direction to tamp the earth under and in contact with said side form, means mounting said tamper on said carriage, and means for actuating said tamper to continuously and rapidly deliver tamping blows upon the earth while said carriage is being continuously advanced in said one relation with said side form.

2. A machine for tamping earth under a concrete side form which rests directly upon the ground, comprising a carriage constructed to travel upon said side form and to maintain one relation with said side form during the whole of its travel, twin tamping means mounted on said carriage and spaced apart laterally to straddle said side form, said twin tamping means being constructed and positioned to tamp the earth under and in contact with said side form, and means for actuating said twin tamping means to continuously and rapidly deliver tamping blows upon the earth while said carriage is being continuously advanced in said one relation with said side form.

3. A machine for tamping earth under a concrete side form which rests directly upon the ground, comprising a carriage constructed to

travel upon said side form and to maintain one relation with said side form during the whole of its travel, vertically elongated substantially parallel tamper mounts mounted on said carriage and having their lower ends projecting downwardly from said carriage to straddle the side form, tampers mounted on said lower ends of said tamper mounts, said tampers being constructed and positioned to tamp the earth under and in contact with the side form, and means for actuating said tampers to continuously and rapidly deliver tamping blows upon the earth while said carriage is being continuously advanced in said one relation with said side form.

4. A machine for tamping earth under a concrete side form which rests directly upon the ground, comprising a carriage constructed to travel upon said side form, vertically elongated tamper mounts mounted on said carriage and having their lower ends projecting downwardly from said carriage to straddle the side form, tampers carried by said lower ends of said tamper mounts, said tampers being constructed and positioned to tamp the earth under and in contact with the side form, a transverse shaft mounted near the upper ends of said tamper mounts and having eccentrics at the outer sides of the latter, means on the carriage for driving said shaft, and actuating connections between said eccentrics and said tampers.

5. A machine for tamping earth under a concrete side form which rests directly upon the ground, comprising a carriage constructed to travel upon said side form, two vertically elongated tamper mounts disposed at opposite sides of said carriage and projecting both upwardly and downwardly therefrom, the lower ends of said mounts being adapted to straddle the side form, means mounting said tamper mounts upon said carriage, bearings carried by the upper ends of said tamper mounts, a transverse shaft mounted in said bearings and having eccentrics at the outer sides of said tamper mounts, tampers mounted on the lower ends of said tamper mounts, actuating connections between said eccentrics and said tampers, and driving means for said shaft mounted on said carriage.

6. A machine for tamping earth under a concrete side form which rests directly upon the ground, comprising a carriage constructed to travel upon said side form, two vertically elongated tamper mounts which project downwardly from said carriage, the lower ends of said tamper mounts being positioned to straddle the side form, a transverse shaft mounted near the upper ends of said tamper mounts, means mounting said tamper mounts upon said carriage and including means pivotally mounting one of said tamper mounts on an axis substantially co-axial with said shaft allowing upward swinging of said one of said tamper mounts about said axis, means for normally holding said one tamper mount against swinging, tampers mounted on the lower ends of said tamper mounts, said tampers being constructed and positioned to tamp the earth under and in contact with the side form, operating connections between said shaft and said tampers, and driving means for said shaft mounted on said carriage.

7. A machine for tamping earth under a concrete side form which rests directly upon the ground, comprising a carriage to travel upon the side form, said carriage having a base which overlies said side form, a vertically elongated

tamper mount at one side of said base, said tamper mount being rigidly secured to said base and projecting both upwardly and downwardly therefrom, a vertically elongated plate at the opposite side of said base, said plate being rigidly secured to and projecting upwardly from said base, a transverse tie member extending between and secured to the upper ends of said plate and tamper mount, a second vertically elongated tamper mount pivotally mounted for vertical swinging at the outer side of said plate, the two tamper mounts being provided with alined shaft bearings, said bearings and the pivotal axis of said second tamper mount being substantially co-axial, a driven shaft mounted in said bearings, tampers mounted on the lower ends of said tamper mounts, operating connections between said shaft and said tampers, and means for normally holding said second tamper mount against upward swinging.

8. In a machine for tamping earth under a concrete side form resting directly upon the ground, a carriage constructed to travel on the side form, a tamper mount carried by said carriage and projecting downwardly therefrom, a tamper guide secured to the lower end of said mount and declining inwardly transversely of the carriage, a reciprocatory tamper slidably engaged with said guide, a bell crank fulcrumed on said mount and connected with said tamper, a driven eccentric above said bell crank, and connecting means between said eccentric and bell crank.

9. In a tamping machine, a carriage, a vertically elongated channel bar mounted on said carriage, a bearing secured in the upper end of said channel bar, a tamper guide secured in the lower end of said channel bar, a tamper slidably engaged with said tamper guide, a shaft rotatable in said bearing, and actuating connections between said shaft and said tamper.

10. In a tamping machine, a carriage, a vertically elongated channel bar mounted on said carriage, a bearing secured in the upper end of said channel bar, a tamper guide secured in the lower end of said channel bar, a tamper slidably engaged with said tamper guide, a bell crank fulcrumed in said channel bar above said tamper and connected with the latter, a shaft rotatable in said bearing and having an eccentric above said bell crank, and connecting means between said eccentric and said bell crank.

11. In a tamping machine, a carriage having a tamper guide, a tamper slideable through said guide, a bell crank fulcrumed on the carriage above said tamper and pivotally connected with the latter, a shaft mounted above said bell crank transverse to the fulcrum thereof and having an eccentric, and a pitman connecting said eccentric with said bell crank.

12. In a tamping machine, a carriage having a tamper guide, a tamper slideable through said guide, a bell crank fulcrumed on the carriage above said tamper and pivotally connected with the latter, a shaft mounted above said bell crank transverse to the fulcrum thereof and having an eccentric, a block rotatably engaged with said eccentric, a second block and pivot means pivotally connecting it with said bell crank, two yokes straddling said blocks respectively and pivoted thereto on axes at right angles to the axes of said eccentric and said pivot means, and connecting means between said yokes.

13. In a tamping machine, a carriage having a tamper guide, a tamper slideable through said

- guide, a bell crank fulcrumed on the carriage above said tamper and pivotally connected with the latter, a shaft mounted above said bell crank transverse to the fulcrum thereof and having an eccentric, a block rotatably engaged with said eccentric, a second block and pivot means pivotally connecting it with said bell crank, two yokes straddling said blocks respectively and pivoted thereto on axes at right angles to the axes of said eccentric and said pivot means, a rod connecting said yokes and slidably engaged with at least one thereof, and a coiled compression spring around said rod and abutting said yokes. 5
14. In a machine for tamping earth under a concrete side form resting directly upon the ground, a carriage constructed to travel along said side form, a vertically elongated plate secured to said carriage at one side of the latter, a vertically elongated tamper mount at the outer side of said plate, means pivotally mounting said mount on said plate for swinging to a raised position, means for normally holding said mount against swinging, a tamper mounted on the lower end of said mount, and operating means for said tamper. 10
15. In a machine for tamping earth under a concrete side form resting directly upon the ground, a carriage constructed to travel along said side form, a vertically elongated plate secured to said carriage at one side of the latter, said plate having an opening near its upper end, a vertically elongated tamper mount at the outer side of said plate having a bearing aligned with said opening, a driven tamper-operating shaft passing through said opening and said bearing, means surrounding said shaft and pivotally mounting said mount on said plate for swinging to a raised position, means for normally holding said mount against swinging, a tamper mounted on the lower end of said mount, and actuating connections between said shaft and said tamper. 15
16. In a machine for tamping earth under a concrete side form resting directly upon the ground, a carriage constructed to travel along said side form, a vertically elongated tamper mount at one side of said carriage, said mount having a bearing transverse to the carriage, a transverse driven tamper-operating shaft mounted in said bearing, means surrounding said shaft and mounting said mount on said carriage for upward swinging, means for normally holding said mount against swinging, a tamper mounted on the lower end of said mount, and actuating connections between said shaft and said tamper. 20
17. In a machine of the class described embodying a carriage adapted to travel upon a rail when the machine is in use; a transporting wheel for said carriage, an arm carrying said wheel, a horizontal shaft carrying said arm and extending transversely of the carriage, means slidably and rotatably mounting said shaft on the carriage, spring means for sliding said shaft in one direction, and an abutment on the carriage under which said arm is adapted to snap under the influence of said spring means when swung downwardly to lower the transporting wheel for use. 25
18. In a machine of the class described embodying a carriage adapted to travel upon a rail when the machine is in use; a normally raised transporting wheel at the front end of the machine, means for holding said wheel in lowered position when required, a rearwardly inclined bearing rigidly carried by the rear end of said carriage, a transporting handle having an oblique front end rotatably received in said bearing, whereby said handle may occupy either a raised or a lowered position, and means for holding said oblique handle end against rotation in said bearing when desired. 30
19. A machine for tamping earth along and under a side form comprising a carriage, means for guiding said carriage along said side form and for maintaining one relation between said side form and carriage during the whole travel of the latter, tamping means carried by said carriage, means for actuating said tamping means to continuously deliver tamping blows in quick succession to the earth transversely of the side form in a direction to tamp said material under said member along and under said side form while said guiding means travels thereon and maintains said carriage in said one relation with said side form, and means for vertically adjusting said guiding means to maintain the same elevation of said tamping means relative to the bases of side forms of different heights. 35
20. A machine for tamping earth along and under a side form comprising a carriage to travel upon said side form, tamping means carried by said carriage, guiding means to straddle the top of said side form, and additional guiding means below the first mentioned guiding means to contact with a vertical side of said side form at a point near the base of said form. 40
21. A machine for tamping earth along and under a side form comprising a tamping means, means for guiding said tamping means along said side form during the progression of said tamping operation, and means for simultaneously supplying oil to a side of said side form during the tamping operation. 45
22. A tamping machine comprising a self-propelled carriage constructed to alone travel and alone maintain its balance upon a single side form, and driven tamping means on said carriage for continuously tamping earth along and under the side form while the carriage continuously advances along said side form. 50
23. A tamping machine comprising a self-propelled carriage constructed to alone travel along and alone maintain its balance upon a single side form, and driven twin tamping means on said carriage for continuously tamping earth along opposite sides of and under the side form while the carriage is continuously advancing along said side form, said tamping means having resilient portions preventing them from exerting upward unbalancing thrusts on the carriage tending to tilt the latter from the side form. 55
24. A machine for tamping earth under and along a side form, comprising a carriage, tamping means carried by said carriage for continuously and rapidly delivering tamping blows transverse to the side form in a direction to tamp earth under and along said side form as the carriage advances along the same, and positively driven traction means for advancing said carriage, said traction means being designed to travel upon said side form. 60
25. A machine for tamping earth under and along a side form, comprising a carriage, tamping means carried by said carriage for continuously and rapidly delivering tamping blows transverse to the side form in a direction to tamp earth under and along said side form as the carriage advances along the same, positively driven traction means for advancing said car- 65
- 70
- 75

- riage, said traction means being designed to travel upon said side form, and a single means on the carriage for operating said tamping means and said traction means.
- 5 26. A machine for tamping comprising a carriage constructed to ride directly upon and along a member under which material is to be tamped, and a tamping means automatically operated to continuously and rapidly strike successive tamping blows transverse to said member in a direction to tamp said material under said member as said carriage travels along and upon said member.
- 10 27. A machine for tamping comprising a carriage constructed to ride directly upon and along a member under which material is to be tamped, a tamping means automatically operated to continuously and rapidly strike successive tamping blows transverse to said member in a direction to tamp said material under said member as said carriage travels along and upon said member, and traction means operating upon the member along which said carriage rides to propel said carriage along said member during the tamping operation.
- 15 28. A machine for tamping comprising a carriage constructed to ride directly upon and along a member under which material is to be tamped, a tamping means automatically operated to continuously and rapidly strike successive tamping blows transverse to said member in a direction to tamp said material under said member as said carriage travels along and upon said member, traction means operating upon the member along which said carriage rides to propel said carriage along said member during the tamping operation, and a single means for operating said tamping means and said traction means.
- 20 29. A structure as specified in claim 21; together with means for placing the oil under pressure.
- 25 30. A machine for tamping earth along a concrete side form comprising a carriage, a tamping unit, a transporting wheel, and means for adjusting said transporting wheel between operative and inoperative positions which is of such a structure that the wheel is substantially in line with the center of gravity of the apparatus in either position.
- 30 31. A machine for tamping earth along a concrete side form comprising a carriage, a tamping unit, a transporting wheel and means for adjusting said transporting wheel into such inoperative position that it will roll along said side form.
- 35 32. A machine for tamping earth along and under a concrete side form comprising a carriage, a tamping unit, a transporting wheel, means for adjusting said transporting wheel, and a latch for holding said wheel in any position of adjustment.
- 40 33. A machine for tamping earth along a concrete side form comprising a carriage, a transporting wheel movable into and out of operative position, a traction means for effecting movement of said carriage along said side form, and a handle structure movable to one position for transportation of said machine or to another position at which it is accessible for steadyng said machine on said side form.
- 45 34. A machine for tamping earth along a concrete side form comprising a carriage, means for effecting movement of said carriage along said side form, a handle structure connected to said carriage in such a manner that it is movable to a position for transportation of said carriage and to a second position at which it is accessible for steadyng said carriage on said side form when required, and means for securing said handle structure in either of said positions.
